UNITED STATES PATENT OFFICE

162,393

TOWEL SUPPORT

James E. Donaldson, Chicago, Ill.

Application January 25, 1949, Serial No. 475

Term of patent 14 years

(Cl. D33—16)

To all whom it may concern:

Be it known that I, James E. Donaldson, a citizen of the United States and resident of Chicago, in the county of Cook and State of Illinois, have invented a new, original, and ornamental Design for a Towel Support, of which the following is a specification, reference being had to the accompanying drawing, forming a part thereof.

In the drawing

I claim:

The ornamental design for a towel support, as shown.

JAMES E. DONALDSON.
